DESIGN FOR AN EASY CHAIR

Charles Eames, West Los Angeles, Calif., assignor
to Evans Products Company, Detroit, Mich., a
corporation of Delaware

Application March 27, 1947, Serial No. 137,932

Term of patent 14 years

(Cl. D15—1)

To all whom it may concern:

Be it known that I, Charles Eames, a citizen of the United States, residing at West Los Angeles, in the county of Los Angeles and State of California, have invented a new, original, and ornamental Design for an Easy Chair, of which the following is a specification, reference being had to the accompanying drawing, forming a part thereof.

Figure 1 shows a side elevational view of an easy chair, embodying my new design.

Figure 2 shows a front elevational view thereof.

Figure 3 shows a rear elevational view thereof.

Figure 4 shows a perspective view thereof.

I claim:
The ornamental design for an easy chair, as shown.

CHARLES EAMES.
